UNITED STATES PATENT OFFICE

172,590

WALL SHELF

Frank Galante, Malden, Mass.

Application September 21, 1953, Serial No. 26,885

Term of patent 7 years

(Cl. D33—3)

To all whom it may concern:

Be it known that I, Frank Galante, a citizen of the United States, residing at Malden, in the county of Middlesex and State of Massachusetts, have invented a new, original, and ornamental Design for a Wall Shelf, of which the following is a specification, reference being had to the accompanying drawing, forming a part thereof.

In the drawing:

Fig. 1 is a perspective view of a wall shelf, showing my new design;

Fig. 2 is a top plan view thereof;

Fig. 3 is an enlarged, fragmentary sectional view showing one corner of a shelf and the supporting chain structure.

I claim:

The ornamental design for a wall shelf, as shown and described.
